(57) **CLAIM**

The ornamental design for an incubator, as shown and described.

DESCRIPTION

FIG. 1 is a front, top and right perspective view of an incubator, showing our new design;

FIG. 2 is a front, top and left perspective view thereof;

FIG. 3 is a front elevational view thereof;

FIG. 4 is a rear elevational view thereof;

FIG. 5 is a left side devotional view thereof;

FIG. 5 is a right side elevational view thereof;

FIG. 7 is a top plan view thereof; and,

FIG. 8 is a bottom plan view thereof.

The broken lines in the figures illustrate portions of the article that form no part of the claimed design.
